CLAIM

The ornamental design for a shower head, as shown and described.

DESCRIPTION

FIG. 1 is a front, bottom, perspective view of a shower head, showing our new design;

FIG. 2 is a right side elevation view thereof;

FIG. 3 is a rear elevation view thereof;

FIG. 4 is a front elevation view thereof;

FIG. 5 is a left side elevation view thereof;

FIG. 6 is a top plan view thereof;

FIG. 7 bottom plan view thereof; and,

FIG. 8 is a top perspective view.

The broken lines shown represent portion of a shower head and form no part of the claimed design.

1 Claim, 8 Drawing Sheets(56)
